UNITED STATES PATENT OFFICE.

JONATHAN SUMNER JONES, OF WEST BEND, IOWA, ASSIGNOR OF ONE-HALF TO NICOLL Y. HASLEY, OF PEORIA, ILLINOIS.

RAILWAY-SWITCH.

No. 874,011.

Specification of Letters Patent.

Patented Dec. 17, 1907.

Application filed May 13, 1905. Serial No. 260,222.

To all whom it may concern:

Be it known that I, JONATHAN SUMNER JONES, a citizen of the United States, residing at West Bend, in the county of Palo Alto 5 and State of Iowa, have invented certain new and useful Improvements in Railway-Switches, of which the following is a specification.

My invention relates to improvements in 10 means for opening and closing railway switches, and consists particularly in improvements in the mechanism shown in United States Patent No. 742,996, bearing date of November 3, 1903.

15 To this end my invention consists in providing certain safety devices to prevent derailing of the car or breaking any of the switch actuating mechanism where the switch is clogged, and consists in other improved features of construction hereinafter 20 described and claimed.

In the accompanying drawings forming part of this specification, Figure 1 is a plan view of a section of a street railway track 25 and branch track and a switch with my improved mechanism arranged in connection therewith, the switch being shown in position to allow the car to pass on a straight track; Fig. 2 is an enlarged inverted horizontal 30 sectional view of a metal box designed for holding part of my improved mechanism, and Fig. 3 is an enlarged longitudinal sectional view of the box.

In the drawings 2 and 3 designate the parallel fixed rails of the main track, and 4 and 5 curved rails extending from the main rails to form a side track.

6 represents an ordinary pivoted switch tongue, and 7 and 8 are guard rails. Boxes 40 9 and 10 are sunk between the tracks and provided with suitable covers 11 and 12. A plate 13 is fixed in engagement with the covers 11 and 12 and curved guide-bars 14 and 15 are formed on, or fixed to, the top of 45 the plate to direct the lever arm carried by the car, as hereinafter set forth, into and through the open space between the boxes. An inclined plate 16 is supported below the covers under the intermediate slot for the 50 purpose hereinafter set forth. The cover 11 is provided with a slot 17, a bell-crank lever 18 being fulcrumed under the cover at the inner end of said slot. Pivots supported on the cover of the box is an elbow shaped 55 lever 19 having link connection 20 with the

bell-crank lever 18 in such manner that the two levers will be operated jointly to turn the switch tongue 6 into open position, one end of the elbow lever 19 extending across the opening between the boxes as shown in 60 Fig. 2. The opposite end of the lever 19 is connected by a link 21 with the underside of the switch tongue 6. The link 21 is formed with a longitudinal slot 22 to constitute a 65 slidable connection with the switch tongue. The switch tongue is normally held in closed position by means of a spring 23 surrounding a rod 24 inside the box 9, the rod 24 being connected at its outer end with the switch tongue, as shown in Fig. 2.

Having pivotal support 25 under the front platform 26 of the car is the rearwardly extending arm 27. The arm is normally held in raised position by means of a spring 28 surrounding a vertical rod 29 which has link 70 connection 30 at its lower end with the arm 27 and at its upper end extends through the platform of the car. The spring 28 bears at one end against the bracket 31 and at its opposite end against a plate 32 secured upon 80 the rod. Having pivotal support 33 on the rear end of the arm 27 is a bell-crank lever 34 supporting a wheel 35 at its lower end. The wheel lever 34 is held in normal position by a coil spring 36 interposed between its forward end and the underside of the arm 27. 85

Operation. Fig. 2 shows by full lines the switch in closed position. As the car travels forward upon the track the wheel bearing lever carried by the end of the arm 27 will 90 pass into the slot between the boxes, striking the end of the lever 19 and turning it into the dotted position shown in Fig. 2 opening the switch. This operation will throw the lever 18 upward through the slot 17 through the 95 medium of the connected link 20. The levers are so connected that they will remain in this position until the lever 18 is mechanically returned to normal position as by means of suitable devices, not shown, carried 100 by the car.

The two essential features of improvement in the construction shown are the spring devices 23 and 36. The spring 23 being arranged within the box 9 will normally hold 105 the switch closed without being in a position where it can be clogged by dirt or struck by passing wagons, etc.

The spring device 36 arranged in connection with the wheel bearing lever 34 will ordi- 110

narily hold the wheel bearing lever 34 in position to actuate the lever 19, but where the switch has become clogged so that it cannot be opened the spring 36 will give, allowing 5 the wheel bearing lever 34 to ride over the lever 19, and thus prevent derailing of the car or injury to the switch actuating mechanism.

Having now described my invention, what 10 I claim as new, and desire to secure by Letters Patent, is:—

1. In combination with a railway switch and car, means for actuating said switch consisting of a rearwardly extending arm pivotally supported underneath the car, a spring normally holding said arm in raised position, a bell crank lever fulcrumed upon the rear end of said arm and carrying a wheel at its lower end, and a spring support for the 20 opposite end of said lever.

2. In combination with a railway switch and car, a chamber arranged alongside said switch and formed with a slot parallel therewith, a spring supported within said chamber 25 and connected with said switch to hold the same in closed position, a lever arm ful-

crumed in said chamber and connected with said switch, said arm extending into said slot, and a downwardly extending arm carried by said car in position to enter said slot 30 and actuate said lever arm to open the connected switch.

3. In combination with a railway switch and car, a chamber arranged alongside said switch, a spring supported within said chamber and connected with said switch to hold the same in closed position, lever mechanism supported in said chamber and connected with said switch, a portion of said mechanism extending through a slot parallel with said switch, and a downwardly and rearwardly extending wheel supporting arm carried by said car platform in position to enter said slot and actuate said lever mechanism to open the connected switch. 40 45

In testimony whereof I affix my signature in presence of two witnesses.

JONATHAN SUMNER JONES.
